UNITED STATES PATENT OFFICE.

GEORGE E. ROBERTS AND JOHN C. SULLIVAN, OF VALLEY FALLS, RHODE ISLAND.

BLOWPIPE FOR BURNING GAS MIXTURES.

No. 904,452.

Specification of Letters Patent.

Patented Nov. 17, 1908.

Application filed May 8, 1908. Serial No. 431,692.

To all whom it may concern:

Be it known that we, GEORGE E. ROBERTS and JOHN C. SULLIVAN, citizens of the United States, residing at Valley Falls, in the county of Providence and State of Rhode Island, have invented new and useful Improvements in Blowpipes for Burning Gas Mixtures, of which the following is a specification.

10 This invention relates to a blow pipe for burning a suitable gas mixture, and relates more particularly to improvements whereby the volume of either air or gas can be readily varied without materially affecting the pressure at the orifice or nozzle of the blow pipe.

15 The invention has for one of its objects to improve and simplify the construction and operation of devices of this character so as to be comparatively easy and inexpensive to manufacture, readily manipulated, and composed of comparatively few parts.

20 Another object of the invention is the provision of a blow pipe consisting of a body having separate chambers for the air and gas inflow and having a nozzle piece communicating with the gas chamber and into which extends a threaded tube that communicates with the air chamber for delivering a jet of air into the nozzle piece at the orifice thereof, there being a needle valve arranged in the said tube whereby the volume of gas or air can be independently regulated.

25 30 35 With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, Figure 1 is a central longitudinal section of the blow pipe. Fig. 2 is a side elevation of the air-conducting tube thereof. Fig. 3 is a similar view of the needle-controlling valve.

40 45 50 Similar reference characters are employed to designate corresponding parts throughout the several views.

55 Referring to the drawing, A designates a cast metal or other body that is formed with separate inlet passages 1 and 2 that are internally threaded at 3 and 4, for the reception of pipes connected with a source of gas and air or other fluid under pressure, the

body being formed with chambers 5 and 6 separated by a partition 7 and communicating, respectively, with the inlet passages 1 and 2. The outer end of the chamber 5 is internally threaded at 8 for receiving the inner end of a hollow tubular nozzle piece 9 that has its outer end contracted at 10 and provided with a jet opening or orifice 11.

The partition 7 has a threaded opening 12 in which screws an air-conducting tube 13 of smaller diameter than the nozzle piece and chamber 5, so that gas can freely pass around the said tube to the orifice of the nozzle piece and this tube has one or more openings 14 for communication with the air chamber 6 so that air can flow through the said tube to the orifice of the nozzle piece and mix with the gas, and at the same time, force the latter from the nozzle piece. The discharge end of the tube 13 is contracted at 15 and has an orifice 16 alining with the nozzle orifice 11 so that the jet of air will flow in a straight line out of the latter and suck the gas therewith from all points around the point 15 of the tube. This tube is adjustable back and forth to vary the volume of gas, and for this purpose, the tube extends out of the chamber 6 at the rear through a plug 18 that has a threaded aperture 17, and on this projected end of the tube is a collar or ring 19 adjustable to any position and clamped in place by a set screw 20, the periphery of the ring being milled so as to afford a better grip thereon. Thus, 80

85 90 95 by turning the collar or ring in one direction or the other, the tube will be correspondingly turned and moved longitudinally nearer to or away from the contracted nozzle portion 10 so as to vary the area of gas outlet. On the rear extremity of the tube 13 is threaded a cap nut 21 which is externally milled, and secured to the cap nut is a needle valve 22 that is of greater length than the tube 13 so as to project to the forward end of the latter where it is formed into a point 23 that cooperates with the air orifice 16 for the purpose of varying the effective outlet area of the said tube. By turning this cap nut 21 while the tube is held stationary by gripping the ring 19, the needle valve can be moved longitudinally to vary the effective air outlet opening. When the tube 13 is adjusted by the turning of the ring 19, the position of the needle valve will not be altered so that the gas volume can be changed independently. With a burner

of this character, the proportions of air and gas can be nicely adjusted to produce an intense blue flame of any desired volume.

From the foregoing description, taken in connection with the accompanying drawing, the advantages of the construction and of the method of operation will be readily apparent to those skilled in the art to which the invention appertains, and while we have 10 described the principle of operation of the invention, together with the device which we now consider to be the best embodiment thereof, we desire to have it understood that the device shown is merely illustrative, and 15 that such changes may be made when desired as are within the scope of the appended claims.

Having thus described the invention, what we claim is:

- 20 1. In a blow pipe, the combination of a body having separate gas and air chambers and inlet passages communicating therewith, a partition separating the chambers and having an opening, a nozzle piece connected 25 with the body and communicating with the gas chamber, an air-conducting tube threaded in the opening of the partition extending into the nozzle piece at one end and out of the body at the opposite end, said 30 tube having an opening communicating with the air chamber, a needle valve disposed within the tube for controlling the outlet opening of the latter, an adjusting member closing and threaded on the outer end of the 35 tube for moving the needle valve back and forth, a wheel screwed on the tube between the said member and end of the body for moving the tube back and forth by rotary movement to vary the effective outlet of the 40 gas and outlet of the nozzle piece, and means for clamping the wheel to the tube.
2. A blow pipe comprising a body having separate air and gas chambers divided by a partition, said partition having a threaded 45 opening extending from one side to the other, a tubular nozzle detachably secured to the body to communicate with the gas chamber thereof and having a frusto-conical discharge end disposed axially in alignment 50 with the said threaded opening of the partition, a cap nut attached to the body to close the air chamber and provided with a threaded opening alining with that of the partition, said body having supply passages 55 communicating with the respective cham-

bers, an air-discharging tube of greater length than the length of the nozzle and body combined and projecting at one end out of the body and having its opposite end contracted and terminating adjacent the frusto-conical end of the nozzle, a continuous screw thread on the tube extending from one end inwardly to an intermediate point for engaging the threaded openings of the nut and partition for moving the tube longitudinally 60 by a rotary movement, the threaded portion of the tube having air inlet openings communicating with the air chamber, a member threaded on and rigidly secured to the projecting end of the tube for turning the latter, 65 a needle valve disposed within the tube and having one end arranged to vary the effective opening at the said contracted end, a device movably mounted and threaded on the projecting end of the tube and connected 70 with the needle valve for regulating the latter, said device forming a closure for the outer end of the tube.

3. In a blow pipe, the combination of a single piece body having separate air and gas chambers, a nozzle piece on the body and communicating with the gas chamber and provided with a discharge orifice, an air tube arranged within the body and extending into the nozzle piece and provided with an opening intermediate its ends for communicating with the air chamber, said tube being of greater length than the combined length of the body and nozzle piece to project out of the rear end of the body, a thread on the 80 tube extending from the outer end to a point adjacent the middle thereof and engaging the body to move back and forth by a rotary movement, an adjusting wheel screwed on the said thread of the tube and clamped 85 thereto, a nut engaging the thread on the extremity of the tube and closing the outer end of the latter, and a needle valve rigidly secured to the nut and extending the full length of the tube and having a point co-operating with the discharge orifice of the latter.

In testimony whereof we affix our signatures in presence of two witnesses.

GEORGE E. ROBERTS.
JOHN C. SULLIVAN.
